Primary Examiner — Marie D. Fast Horse*Assistant Examiner* — Altaira J Swangin(74) *Attorney, Agent, or Firm* — Birch, Stewart, Kolasch & Birch, LLP(57) **CLAIM**

The ornamental design for a videoconferencing monitor, as shown and described.

DESCRIPTION

1. Videoconferencing monitor
  - 1.1 : Front perspective view
  - 1.2 : Rear perspective view
  - 1.3 : Front view
  - 1.4 : Rear view
  - 1.5 : Left view
  - 1.6 : Right view
  - 1.7 : Top view
  - 1.8 : Bottom view
  - 1.9 : Partial enlarged front perspective view of area '1.9' in Fig. 1.1
  - 1.10 : Partial enlarged front perspective view of area '1.9' in Fig. 1.1 in an alternate configuration of use
  - 1.11 : Partial enlarged front perspective view of area '1.9' in Fig. 1.1 in another alternate configuration of use
- This article is a monitor for a non-face-to-face video conference which includes a camera, microphone, speaker and whiteboard function. The even-dash broken lines shown in

(Continued)

the reproductions depict portions of the videoconferencing monitor and form no part of the claimed design. Reproduction **1.9** is a partial enlarged view of the camera part shown in reproduction **1.1**. Reproductions **1.10** and **1.11** are enlarged partial views showing the use states when the camera is rotated to a position inside the housing when it is not used. The dot-dot-dash broken lines in reproductions **1.1**, **1.9**, **1.10** and **1.11** illustrate the boundaries of the enlarged views and form no part thereof.
